(57) **CLAIM**

The ornamental design for a modular detachable stem, as shown and described.

DESCRIPTION

FIG. 1 is a top perspective view showing the top, rear, and left sides of a modular detachable stem;

FIG. 2 is a top perspective view showing the top, rear, and left sides of the modular detachable stem, wherein the right side is a mirror image of the left side;

FIG. 3 is a top perspective view showing the top, front, and left sides of the modular detachable stem, wherein the right side is a mirror image of the left side;

FIG. 4 is a bottom perspective view showing the bottom, rear, and left sides of the modular detachable stem, wherein the right side is a mirror image of the left side;

FIG. 5 is a left side elevation view of the modular detachable stem;

FIG. 6 is a right side elevation view of the modular detachable stem;

FIG. 7 is a front elevation view of the modular detachable stem;

FIG. 8 is a rear elevation view of the modular detachable stem;

FIG. 9 is a top plan view of the modular detachable stem; and,

FIG. 10 is a bottom plan view of the modular detachable stem.

The broken lines in the drawing depict portions of the modular detachable stem and environment that form no part of the claimed design.

1 Claim, 5 Drawing Sheets
